US00D389760S

United States Patent [19]

Mumm et al.

[11] Patent Number: Des. 389,760

[45] Date of Patent: **Jan. 27, 1998

[54] **ELECTRICAL DISTRIBUTION POWER METER DEVICE HAVING AN INTERFACE FOR TELECOMMUNICATIONS SIGNALS**

[75] Inventors: **Paul D. Mumm**, Kansas City; **Mitchel S. Krysa**, Lee's Summit, both of Mo.

[73] Assignee: **Utilicorp Holdings Inc.**, Kansas City, Mo.

[**] Term: **14 Years**

[21] Appl. No.: **68,275**

[22] Filed: **Mar. 25, 1997**

[51] LOC (6) Cl. **10-04**

[52] U.S. Cl. **D10/100**

[58] Field of Search D10/100; 324/110, 324/114, 116, 156, 157; 377/16

[57] CLAIM

The ornamental design for an electrical distribution power meter device having an interface for telecommunications signals, as shown and described.

DESCRIPTION

FIG. 1 is a front elevational view;
FIG. 2 is a right side elevational view;
FIG. 3 is a left elevational view;
FIG. 4 is a rear elevational view;
FIG. 5 is a top plan view; and,
FIG. 6 is a bottom plan view.
